UNITED STATES PATENT OFFICE.

GEORGE H. ROBINSON, OF PITTSBURGH, PENNSYLVANIA.

RAILWAY-TIE AND FASTENER.

1,009,579.

Specification of Letters Patent. Patented Nov. 21, 1911.

Application filed July 29, 1910. Serial No. 574,543.

To all whom it may concern:

Be it known that I, GEORGE H. ROBINSON, a resident of Pittsburgh, in the county of Allegheny and State of Pennsylvania, have 5 invented a new and useful Improvement in Railway-Ties and Fasteners, of which the following is a specification.

This invention relates to metal railway cross ties.

10 The object is to provide a metal tie which is cheap to manufacture, which will securely hold the rails from spreading, which requires no bolts, nuts or like means for fastening the rails, and which enables the rails 15 to be secured thereto and removed therefrom by unskilled laborers.

The invention comprises the tie and fastening means hereinafter described and claimed.

20 In the accompanying drawing Figure 1 shows in side elevation, one-half of my improved tie with the rail in place; Fig. 2 is a plan view of the same; Fig. 3 is a cross section on the line 3—3, Fig. 2; Fig. 4 is a 25 perspective view of one end of the tie with the rail and clamp omitted; Fig. 5 is a detail side view showing means for changing the gage of the track; Figs. 6 and 7 are plan and cross section of a modified form of 30 clamp; Fig. 8 is a perspective view of the wedge; and Fig. 9 is a similar view of the gage changing filler.

The drawings illustrate merely one-half of the tie, the other half being an exact 35 duplicate of that shown. The tie body 1 is shown of substantially —I— shape in cross section. At the end the web is preferably coped off on a diagonal line as shown at 2. The top flanges 3 are separated somewhat 40 from the web and are turned upwardly and inwardly to form the hook-like or overhanging member 4 to receive the outer base flange of the rail 5. Inside of the rail base zone the upper face of the I beam is 45 provided with transverse notches or grooves 6, preferably having an inclined bottom and a square shoulder 7. The clamp 8 is provided with side portions 9 which project downwardly and then toward each other to 50 brace the top flanges of the tie and thereby hold the clamp, and the rail also, from upward movement. Said clamp at its outer end 10 projects over the inner flange of the rail base while its inner end 11 projects over 55 the groove or notch 6. To secure the clamp

in place a wedge 12 is driven into the notch or groove 6. The outer edge of said wedge bears against the downwardly extending side portions 9 of the clamp to force said clamp against the rail, and said wedge has 60 at its inner edge an upwardly projecting part 13 which forms a square shoulder bearing against the inner end of the clamp. This wedge when driven tightly into place not only forces the clamp as a whole against or 65 toward the rail base but also lifts the inner end 11 of said clamp thereby causing the outer end 10 to be depressed to tightly embrace the inner flange of the rail base.

When it is necessary to provide for a 70 variation of gage of the track, such as on curves, the hook-like part 4 will be formed to the maximum width of the track, and when necessary to bring the rails closer together a spacing member 15 is inserted into 75 the hook-like member 4, as shown in Fig. 5. This spacing piece is preferably provided with flanges or shoulders 16 on its edges which embrace the side edges of the member 4 and prevent the filler from escaping 80 sidewise.

To prevent accidental escape of the wedge 12 after being driven into place, the end of said wedge is split so that a part thereof can be bent to one side, as shown at 17, to 85 engage the side of the tie or clamp 8 and thus prevent backward movement of the wedge.

The clamps illustrated in Figs. 1 to 5 are preferably placed on the top flanges or 90 head of the tie before the ends or hooks 4 are turned up. A clamp which can be put on or taken off the top or head of the tie at will, is shown in Figs. 6 and 7. This is made up of two parts 18 and 19 joined 95 along a longitudinal line by interlocking edge portions 20.

The tie described is cheap to manufacture since it can be produced by simple machine operations from an ordinary I-beam of the 100 proper section. The ends can be formed by simple shearing and bending operations, while the transverse notches or grooves can be formed either by the rolls when rolling the section, or by a gang milling machine. The fastening means are of simple and durable construction and require no bolts or like fasteners. The tie will absolutely hold the rails from spreading and the fastening means securely fasten the rails in place. 110

The clamps can be cheaply made from plate metal by simple cutting and bending operations.

What I claim is:

- 5 1. The combination of a rolled metal tie provided with an integral hook portion for receiving one flange of the rail and with a transverse groove or notch, a one-piece clamp arranged to embrace the other flange 10 of the rail, and a wedge adapted to be driven into said groove or notch and arranged to engage the clamp and force the same against the rail base.
- 15 2. The combination of a rolled metal tie 15 of I-shape in cross section having its top flanges severed from the web and bent upwardly to form portions to receive one of the flanges of the rail, a clamp provided with downwardly projecting side portions embracing the top flanges of the tie and overhanging the other flange of the rail and means arranged to be driven under the outer portion of the clamp and acting to move said clamp toward the rail base and simultaneously depress the rail base engaging portion of said clamp.
- 20 3. The combination of a metal tie of I- 20 shape in cross section having its top flanges severed from the web and bent upwardly to 25 form portions overlying one of the flanges of the rail, and provided in its top face with a transverse groove or notch, a clamp provided with depending side portions em-

bracing the top flanges of the tie, and having a portion overlying the other flange of 35 the rail, and a wedge arranged to be driven into the transverse notch or groove and force the clamp against the rail.

4. The combination of a rolled metal tie 40 provided with an integral hook portion for receiving one flange of the rail and with a transverse groove or notch, a filler adapted to be inserted between said hook portion and the rail base, a clamp provided with downwardly projecting side portions 45 embracing the top of the tie and with a portion overhanging the other flange of the rail, and a wedge adapted to be driven into said groove or notch and engage the depending side portions of the clamp and force the 50 same against the rail base.

5. The combination of a metal tie of I- 55 shape in cross section having as portion forced upwardly to overlie a flange of the rail, and a clamp comprising two portions separable on a longitudinal line by endwise relative movements of said portions and provided with downwardly projecting portions arranged to embrace the top flanges of 60 the tie.

In testimony whereof, I have hereunto set my hand.

GEORGE H. ROBINSON.
